ABSTRACT

Spherically contoured tools for use in crystallographic orientation angle connection of crystal plates and the like are formed by machining recesses at appropriate locations on two plates such as lapping plates. For example, a recess is machined around the outer periphery of the first plate and about the inner periphery of the second plate. The plates are then mounted in contact with the faces of contouring gears and subjected to lapping in a planetary lapping machine. A spherically convex contour is imparted to the first plate and a spherically concave contour is imparted to the second plate.

TECHNIQUE FOR GENERATING SPHERICALLY CONTOURED TOOLS

BACKGROUND OF THE INVENTION

1. Field of the Invention

This invention relates to the formation of spherical contours and more particularly to a method of producing spherically contoured tools for such uses as correcting the crystallographic orientation angle of crystal plates.

2. Description of the Prior Art

Spherically contoured tools such as mounting apparatus, grinding or lapping plates, etc., are often required in such applications as contouring optical lenses and the like. In applicant's copending application filed concurrently herewith a method of correcting the orientation angle of crystals by forming mesas on the major surfaces of the crystals and subsequently double face lapping the crystals is described. One technique for forming the mesas by lapping or grinding the crystal to remove a wedge of material therefrom while the crystal was held in a spherically deflected configuration was also described. This technique required either a spherically contoured mounting means or correction tool upon which the crystals were mounted in spherical deflection or a spherically contoured lapping or grinding tool. Further, in one described method of mounting the crystals to the spherically contoured correction tool, a spherically contoured pressure plate is utilized to obtain a uniform bonding layer. The desired accuracies in the described angle correction process require that the spherically contoured tools, etc., be very precise. The amount of angle correction provided thereby depends in part upon the degree of contour of the correction tool. Accordingly it is desirable to be able to generate a variety of spherical contours for correction tools.

At present, spherically contoured tools may be formed by machining in a lathe or similar apparatus. However tools formed by this procedure are relatively expensive because of the machining time involved and the accuracy thereof may not be as good as required. Further a new machine setup or calibration procedure is required for each different spherical contour desired. Other methods of forming spherical contours also exist but they also have the foregoing disadvantages of high cost and lack of flexibility to provide a range of contours without requiring recalibration of the apparatus being utilized.

Accordingly it is an object of this invention to improve the methods of generating spherically contoured tools so that a wide range of contours can be provided by one basic generating apparatus arrangement.

Another object is to improve the methods of generating spherically contoured tools to provide more accurate tools.

Still another object is to simplify the methods of generating spherically contoured tools to reduce the time and costs required for generating such tools.

SUMMARY OF THE INVENTION

The foregoing objects and others are achieved in accordance with the principles of the invention by utilizing a standard planetary double face lapping machine. Recesses are machined or otherwise formed at selected locations in two plates such as two lapping plates. For

example, one plate can have a recess machined around the outer periphery thereof and the other plate can have a recess machined around the inner periphery thereof. Contouring gears, normally utilized for reconditioning out-of-flatness lapping plates, are then placed between the two plates in a lapping machine. These reconditioning gears rotate about their own vertical center axis as driven by an inner and outer driving gears which are part of a lapping machine. The force balance between the plates and the gears causes more material to be removed from the plates in the vicinity of the recesses. Accordingly the first plate is lapped into a spherically convex contour and the second plate is lapped into a complementary spherically concave contour. The degree of contour can be controlled by monitoring the lapping time so that a wide range of spherical contours can be obtained without varying the lapping procedure. The type of contour obtained can be varied by changing the locations of the recesses.

BRIEF DESCRIPTION OF THE DRAWING

The invention will be more fully comprehended from the following detailed description and accompanying drawing in which:

FIG. 1 is an exploded perspective view of a contouring gears mounted between two lapping plates;

FIG. 2 is a sectional view along line 2-2 of FIG. 1;

FIG. 3 is a sectional view similar to FIG. 2 after the plates have been lapped by the contouring gears;

FIG. 4 is a sectional view of a plate during a process of forming two unrelated contours on a surface thereof; and

FIG. 5 is a sectional view of the apparatus of FIG. 4 after the completion of the formation of two unrelated spherical contours on a surface of the plate.

DETAILED DESCRIPTION

The technique of this invention is based upon the fact that in a planetary double face lapping machine a state of equilibrium exists between the forces exerted by the upper and lower lapping plates of the machine upon any item such as a crystal plate being lapped between the upper and lower lapping plates. Accordingly if one lapping plate has a small area of contact with the item being lapped than the corresponding portion of the other lapping plate, the force per unit area presented by the first lapping plate must be greater than that of the second lapping plate in order to maintain the force equilibrium. The higher the force per unit area, the greater the amount of material removed per lapping stroke. The upper and lower lapping plates of a planetary double face lapping machine can themselves be lapped into spherical contours and subsequently utilized as correction tools, etc., by using the foregoing fact of force equilibrium as will now be discussed.

In the course of normal usage the lapping plates of a lapping machine will lose their desired flat condition. Accordingly, special lapping plates commonly called contouring gears are utilized to recondition out-of-flatness lapping plates to the desired flat condition. As shown in an exploded perspective view in FIG. 1, the contouring gears 10 are placed between upper and lower lapping plates 12 and 14, respectively, and lapped therewith in the lapping machine to recondition surfaces 16 and 18, respectively. Contouring gears 10 rotate about their own respective axes 10a and are

driven by inner and outer driving gears, not shown, which constitute part of a standard lapping machine.

In accordance with this invention, recesses are machined in plates 12 and 14 at strategic locations so that the subsequent lapping with contouring gears 10 generates spherical contours on surfaces 16 and 18 rather than returning these surfaces to a flat condition. As shown more clearly in the sectional view of FIG. 2, in one embodiment a recess 20 is formed around the outer periphery of surface 16 of plate 12 and a recess 22 is formed around the inner periphery of surface 18 of plate 14. Recesses 20 and 22 can be formed by machining or other well known techniques.

These recesses 20 and 22 cause the forces per unit area in section 24 of plate 12 to be greater than the corresponding forces per unit area in section 26 of plate 14 because section 24 has a smaller area of contact with gears 10 but the total forces must be in equilibrium as previously discussed. Correspondingly, the force levels in section 30 of plate 14 are greater than the corresponding force levels in section 28 of plate 12. Accordingly, during the subsequent lapping process more material is removed from sections 24 and 30 than from sections 26 and 28, respectively, by contouring gears 10. As indicated in the sectional view of FIG. 3 in an exaggerated form, this results in surface 16 being lapped into a spherically convex contour and surface 18 being lapped into a spherically concave contour. Spherically concave contoured plate 14 can be used as the correction tool in the angle correction process for crystal plates previously referenced and spherically convex contoured plate 12 can be utilized as the pressure plate in the same process.

The widths 32 and 36 of recesses 20 and 22, respectively, determine the force levels and consequently the rate at which the spherical contours are formed. The progress of the contoured surfaces 16 and 18 can be checked periodically using a spherometer and the lapping operation can be terminated when the desired contour is reached. The shape of the contour increases with lapping time until recesses 21 and 22 have been completely removed at which point the contoured shape stabilizes and does not change with further lapping. Consequently lapping time can be used as a very good control of the contour once the particular lapping speeds, abrasive size, etc., have been selected. If desired, the depths 34 and 38 of recesses 20 and 22, respectively, can be predetermined, taking into account the other factors of lapping speed, abrasive size, etc., so that these recesses disappear at precisely the desired contour. Thus periodic monitoring of the contours can essentially be eliminated. Alternatively, a plurality of recesses can be positioned on surfaces 16 and 18 to either aid or oppose each other in order to freeze or stabilize a particular spherical contour at some stage of the lapping operation.

Although recesses are shown in both plates 12 and 14 in the foregoing embodiment a single recess can be used in only one of the plates to produce the spherical contour. Alternatively, as already mentioned, a plurality of recesses can be utilized in each plate. The rate of generation of the spherical contour and the exact configuration thereof will of course depend upon the number, locations and dimensions of the recesses.

It should be apparent from the foregoing discussion that a wide range of contours can be obtained from the

same basic procedure by merely controlling the lapping times and characteristics of the recesses. This flexibility is very important in providing spherically contoured tools for various applications.

In a second embodiment of the method of the invention, two entirely unrelated contours can be formed on different portions of a surface of a correction tool. Such a tool advantageously could be utilized, for example, in the referenced angle correction process to increase the usable mounting surface of a correction tool for correcting all crystal plates mounted thereon by substantially identical amounts. In the first step of this embodiment, a single spherical contour is formed on an entire surface of the tool or plate as discussed with respect to the contour on surface 18 of tool or plate 14 in FIG. 3. Subsequently, a portion 44 of the surface 18 is reconditioned into a flat condition as shown in FIG. 4. This can be accomplished, for example, by lapping tool or plate 14 in a lapping or grinding machine by well known techniques.

After the formation of flat portion 44, a recess 58 is formed around the outer periphery of the flat portion 44 of plate 14 by techniques previously discussed. Plate 14 is then subjected to further lapping in a double face lapping machine by contouring gears 11 as shown in FIG. 4. A pressure plate 46 holds contouring gears 11 in contact with plate 14. Pressure plate 46 is provided with a recess 48 about its inner periphery. The width 54 of recess 48 as compared with the width 56 of pressure plate 46 is determined by the width 52 of flattened portion 44 as compared with the total width 50 of tool 14. The width 52 of flattened portion 44 advantageously may equal approximately one-half of width 50 so that the width 54 of recess 48 equals one-half of width 56. Because of the force balances between gears 11, plate 14 and pressure plate 46, more material is removed from the recessed edge of flat portion 44, i.e., from the outer periphery thereof, than from the inner periphery. Accordingly, portion 44 is lapped into a spherical contour as shown in FIG. 5 which is unrelated to the contour on the remaining portion 45 of surface 18. Portions 44 and 45 can have the same or different degrees of contours as desired.

Crystal plates to be corrected can be mounted on both contoured portions 44 and 45 and simultaneously corrected by a single flat lapping or grinding plate as discussed in applicant's previously referenced copending application.

Although the foregoing discussion has dealt primarily with the generation of spherically contoured tools for angle correction of crystals, many other applications of the technique are readily apparent. Plates 12 and 14 can be replaced by optical blanks which can be lapped into contoured optical lenses by the indicated procedures. Optical blanks can also be mounted, or otherwise held in place on plates 12 and 14, or contouring gears 10 and lapped into spherically contoured optical lenses.

Further, the technique is not limited to lapping but can be utilized with grinding and polishing procedures also.

The technique utilizes standard apparatus available in many crystal and optical device manufacturing shops. The technique is relatively simple and the accuracies obtainable thereby are very good. The production of spherically contoured tools by this technique is

expected to be easier and more economical than by any other existing method.

While the invention has been described with reference to specific embodiments thereof, it is to be understood that various modifications thereto might be made by those skilled in the art without departing from its spirit and scope.

I claim:

1. A method of generating spherically contoured plates comprising the steps of:

forming at least one recess in a first surface of a first one of said plates, said recess being substantially symmetrical with respect to the center of said surface;

placing lapping plates between said first plate and a second one of said plates so that said first surface of said first plate and a first surface of said second plate contact said lapping plates; and

lapping said plates with said lapping plates in a double face lapping machine whereby said first surface of said first plate is lapped into a first spherical contour and said first surface of said second plate is lapped into a second spherical contour complementary to said first contour.

2. The method of claim 1 wherein said recess is formed about the outer periphery of said first surface whereby said first spherical contour comprises a spherical convex contour and said second spherical contour comprises a spherical concave contour.

3. The method of claim 1 wherein said recess is formed at the center of said first surface whereby said first spherical contour comprises a spherical concave contour and said second spherical contour comprises a spherical convex contour.

4. The method of claim 1 wherein said first and second plates comprise substantially circular plates having substantially equal first surfaces and having openings though the centers thereof, said first recess is formed about the outer periphery of said first surface of said first plate; and including the step of forming a recess about said opening in said first surface of said second plate whereby said first spherical contour comprises a spherical convex contour and said second spherical contour comprises a spherical concave contour.

5. The method of claim 4 further including the step of monitoring said contours of said first surface of said first and second plates during said lapping step so that said lapping step can be terminated when said contours reach preselected values.

6. The method of claim 4 wherein said recesses are dimensioned so that said contours have desired values when said recesses have been removed by said lapping

step whereby said contours are retained during any additional lapping.

7. The method of claim 1 wherein said first and second plates comprise the upper and lower lapping plates of said machine and said lapping plates comprise contouring gears for resurfacing said lapping plates.

8. The method of claim 1 further including the steps of:

lapping said first plate in a lapping machine to remove a portion of said first spherical contour thereon to replace said portion by a flat portion;

forming a second recess around the periphery of said flat portion;

placing lapping plates in contact with said flat portion of said first plate; and

lapping said flat portion with said lapping plates in a double face lapping machine so that said flat portion is lapped into a third spherical contour, whereby two unrelated spherical contours can be formed on different portions of said first surface of said first plate.

9. A method of forming spherical contours on first surfaces of first and second objects comprising the steps of:

forming a recess in said first surface of said first object;

placing lapping plates between said first and second objects in contact with said first surfaces thereof;

lapping said first and second objects with said lapping plates to remove portions of said first surfaces thereof whereby said recess causes said first surface of said first object to be lapped into a first spherical contour and said first surface of said second object to be lapped into a second spherical contour complementary to said first spherical contour.

10. A method for generating spherically contoured lapping plates comprising the steps of:

forming a first recess around the outer periphery of a first surface of a first lapping plate;

forming a second recess about the center of a first surface of a second lapping plate;

placing contouring gears between said first and second lapping plates in contact with said first surfaces thereof; and

lapping said first and second plates with said gears whereby said first surfaces of said first and second plates are spherically contoured because of said first and second recesses.
